GAME BOARD

Clifford B. Malbon, Marblehead, Mass.

Application July 22, 1940, Serial No. 346,699

3 Claims. (Cl. 273—136)

This invention relates to certain improvements in game apparatus of the type in which game pieces or checkers are moved about on a game board, as, for example, in the ancient game of checkers.

Game boards of this type are often supported on the laps of the players, and it frequently happens during the progress of the game that the board is jarred or tilted so that the checkers slide from their places and as a result the game is spoiled, as the players are often unable to remember exactly how many checkers were on the board, or exactly where they were placed.

The object of my invention is to provide a game board and a set of game pieces or checkers in connection therewith which will frictionally engage when the checkers are merely placed on the board, so that, when the board is accidentally jarred or is inclined to even a nearly vertical position, the checkers will remain in the places in which they have been placed and will not be moved from their places unless lifted or actually pushed therefrom.

I accomplish this object by providing a board, the surface of which is covered with a coating of flocking of cotton or other fibrous material, which is adhesively secured thereto so that a multiplicity of minute, short fibers stand erect on the surface, and by coating the engaging surface or surfaces of the checkers in like manner, so that, when the checkers are merely placed on the board, the erect fibers on the board and checkers interlock and prevent the checkers from freely sliding on the board, or from being moved thereon by the action of gravity when the board is tilted even to a nearly vertical position, or from being moved from their positions when the board is accidentally moved suddenly or jarred, the construction permitting the checkers to be slid over the surface of the board nearly as easily as if the flocked surfaces were not present, and in no way interfering with the checkers from being lifted and placed in other positions.

For a more complete disclosure of my invention reference is made to the following specification in connection with the accompanying drawing in which:

Fig. 1 is a plan view of a portion of an ordinary checker board which is provided with an embodiment of my invention.

Fig. 2 is an edge view thereof.

Figs. 3 and 4 are respectively greatly enlarged sectional views of a checker and a portion of the board.

Fig. 5 is a still more greatly enlarged view illus-

trating the character of the frictional engagement.

It will be understood that the disclosure of my invention in connection with an ordinary checker board is merely illustrative and that there are various other well known games of this type with which my invention may be advantageously employed.

In the drawing *a* indicates a section of an ordinary checker board and *b* the checkers, or game pieces which are used in connection therewith, the checkers being adapted to be placed on the board either side up.

According to my invention the playing surface 10 of the board is covered with a suitable adhesive and a flocking *c*, which consists of finely divided short particles of cotton, rayon, or wool fibers, is discharged against the coated surface, the well known methods of applying flocking to various 15 surfaces being employed. By this method, thru the action of static electricity, the short fibers stand erect, or on end, in the adhesive, and are retained in this position. As this condition is hardly describable to the naked eye, all illustration 20 thereof in the drawing is on a greatly enlarged scale. By the same method, the opposite sides, or board engaging surfaces, of the checkers are also provided with a coating of flocking *d*, as indicated in Fig. 3. The entire surface of the 25 board and the surfaces of the checkers are therefore all provided with a multiplicity of minute fibrous projections.

When the checkers, as thus coated, are placed 30 on the coated surface of the board, the projecting fibers interlock, as also illustrated in Fig. 5, so that sliding of the checker by gravity action is prevented when the board is inclined or tipped even to a nearly vertical position, or is jarred by being suddenly forced horizontally.

In the game of checkers, one checker is placed 35 on top of another when a checker has been moved entirely across the board and when this is done the projecting fibers on the engaging surface of the checkers also interlock, so that the checker which is on top will not fall off the other checker when the board is tilted, so that both will be retained in position.

In playing a game, the checkers may be readily 40 pushed from place to place or lifted and moved, the coating of flocking only slightly impeding the movement when the checker is slid and in no way affecting it when the checker is lifted.

The application of the flocking to the board 45 and checkers only slightly increases the cost of

manufacture and greatly increases the convenience in the use of the board.

The term "checkers" is intended to include any form of game pieces which are movable on a board. In some instances, as in chess, the game pieces only have one board engaging surface while in checkers they have two. In some instances the checkers have circular designs carved or impressed therein, so that the entire surface is not effective in engaging the board surface, but the board engaging surface has been found to be of sufficient area to hold the checker in position after the flocking has been applied.

I claim:

1. The combination of a game board, having checkers movable on the surface thereof, the surface of the board and the contacting surfaces of the checkers having apparently smooth surfaces presented by the ends of a multiplicity of flexible fibrous projections minute in all dimensions adapted to interlock sufficiently by the weight of the checkers to increase the frictional engagement of the checkers with the board and to hold them in position with equal effort against unintentional sliding movement in any direction, so that they will not be displaced by gravity action when the board is tilted, the extent of interlocking and the rigidity of the projections being sufficiently small to permit ready inten-

tional sliding movement of the checkers with equal small effort in any direction in contact with the board.

2. The combination of a game board, having checkers movable on the surface thereof, the surface of the board, and the contacting surfaces of the checkers, having a flocking of fibrous material adhesively secured thereto presenting apparently smooth surfaces and forming minute flexible projections on the surfaces to hold the checkers in position with equal effort against unintentional movement in any direction while permitting ready intentional sliding movement of the checkers with equal effort in any direction in contact with the board.

3. The combination of a game board, having checkers movable on the surface thereof, said checkers having oppositely disposed faces for engaging the surface of the board, the faces of said checkers and the surface of the board having a flocking of fibrous material adhesively secured thereto presenting apparently smooth surfaces and forming minute flexible projections on the surfaces to hold the checkers in position with equal effort against unintentional movement in any direction while permitting ready intentional sliding movement of the checkers with equal effort in any direction in contact with the board.
